NOCK SETTERS

John J. McFadden, 224 E. Durham St., Philadelphia, Pa.
Filed Apr. 10, 1962, Ser. No. 186,548
1 Claim. (Cl. 29—200)

In order to obtain true and accurate flight of an arrow, the nock must be in longitudinal alignment with the longitudinal axis and grain of the shaft.

The conventional manner of assembling the nock to the shaft is to apply glue to an end of the shaft, hold the shaft in one hand and the nock in the other hand, move the shaft into the nock and adjust the nock back and forth until, depending on the eye, it is believed that the nock and shaft are in proper alignment.

The object of this invention is to devise novel means for assembling the nock and shaft so that the nock will be in longitudinal alignment with the grain and longitudinal axis of the shaft.

With the foregoing and other objects in view as will hereinafter clearly appear, my invention comprehends novel means for supporting and positioning the nock, novel means for supporting and aligning the shaft, and novel means for clamping the shaft in position until the glue has set.

A further object is to devise novel means to clamp the nock in its aligned position.

A further object is to devise a novel support on which the nock and shaft can be mounted in accurate alignment with each other.

A further object is to devise a novel shaft supporting and aligning tube with a nock receiving cap movably connected with an end of the tube.

For the purpose of illustrating the invention, I have shown in the accompanying drawings preferred embodiments of it which in practice will give satisfactory and reliable results. It is, however, to be understood that the various instrumentalities of which the invention consists can be variously arranged and organized, and I do not therefore desire to be limited except by the scope of the appended claim to the exact arrangement and organization of these instrumentalities as herein set forth.

FIGURE 1 is a top plan view, partly broken away, of a nock setter embodying my invention.

FIGURE 2 is a section on line 2 of FIGURE 1.

FIGURE 3 is a section on line 3 of FIGURE 1.

FIGURE 4 is a sectional detail showing more particularly the nock receiving means and a portion of the shaft of an arrow.

FIGURE 5 is a longitudinal sectional on line 5 of FIGURE 1 showing a nock and shaft in longitudinal alignment and clamped in position.

FIGURE 6 is a sectional elevation of another embodiment of the invention showing the parts in open condition.

FIGURE 7 is a sectional elevation of the parts shown in FIGURE 6 but showing such parts in closed condition.

Similar numerals of reference indicate corresponding parts.

Referring to the drawings:

Referring first to the embodiment of FIGURES 1 to 5, a support 1 of any desired material is provided in its top face with a plurality of longitudinally extending grooves 2 disposed side by side and preferably parallel to each other for the reception of the shafts 3 of the

2

arrows which are to be assembled with nocks 4. The support is provided at opposite sides of the grooves with holes 5 to receive aligning pins 6 for the shaft clamping blocks 7. The blocks 7 are guided by the aligning pins and are provided with actuating rods 8 in threaded engagement with a crossbar 9 on the support.

The support 1 has a crossbar 10 provided with nock receiving recesses 11 which are in longitudinal alignment with the grooves for the shafts.

10 A nock carrying bar 12 is rotatably mounted on the support and has at opposite ends handles 13. This nock carrying bar is adapted to fit into the slots at the rear ends of the nocks and may be tapered for such purpose. Slits 14 in the nock locking bar receive the 15 aligning ribs 15 on the nocks which are conventional. The nocks are secured in aligned position by the nock locking bar 16 having recesses 17 for the nocks and the clamping bar is hinged at one end to the support and the opposite end cooperates with a lock 18.

20 In the embodiment of FIGURES 6 and 7, the support is in the form of an open ended tube 19 having slits 20 at its outer end and provided with a locking ring 21.

A nock receiving cap 22 has a slit 23 for the nock rib and is pivoted at 24 to the inner end of the tube.

25 In the operation of FIGURES 1 to 5, the nocks are assembled on the nock carrying bar with their aligning ribs in the slits 14. The bar 12 is partially rotated to position the nocks in the recess 11 of crossbar 10 and the nock clamping bar is moved into clamping position 30 and locked in place. The shafts of the arrows are placed in their grooves and positioned to have their longitudinal alignment with the nocks, glue applied to the shafts or nocks, and the shafts with their grain in longitudinal alignment with the nocks pushed into the nocks. The 35 clamping blocks are moved into locking position and retained therein until the glue has set or dried.

The operation in FIGURES 6 and 7 in its broad aspects, are the same as in the previous figures. The nocks are assembled in the nock carrying cap in aligned position. 40 The shaft is aligned in its tube support and glue applied and the shaft pushed into the nock and locked in aligned position by moving the locking ring over the slits in the ring.

Having thus described my invention, what I claim as 45 new and desire to secure by letters patent is:

A nock setter comprising a support having a plurality of longitudinally extending grooves, a crossbar on the support having recesses in alignment with said grooves, nock carrying means to move nocks into aligned 50 position in said recesses, means to clamp the nocks in said recesses, said grooves being adapted to receive the shafts, means to align said shafts in their grooves to have their longitudinal axis in longitudinal alignment with the nocks, and means to clamp the shafts in their 55 aligned positions, wherein the nock clamping means comprises a bar hinged at one end to said support and means on the support to lock the other end of the clamping bar in locked position.
